DETACHABLE HANDLE FOR A BEVERAGE CAN OR THE LIKE

Frederick W. Finn, Morristown, N.J., assignor of a fractional part interest to Robert G. Wilson, Morristown, N.J.

Filed June 4, 1973, Ser. No. 366,842

Term of patent 14 years

Int. Cl. D7—99

U.S. Cl. D7—70

FIG. 3

FIG. 1

FIG. 2

FIG. 5

FIG. 6

FIG. 1 is a side elevational view of a detachable handle for a beverage can or the like;

FIG. 2 is a front elevational view thereof as seen from the right of FIG. 1;

FIG. 3 is a rear elevational view as seen from the left of FIG. 1;

FIG. 4 is an isometric view thereof;

FIG. 5 is a fragmentary rear elevational view of a modification of the uppermost channel of the design of FIG. 1; and

FIG. 6 is a fragmentary perspective view of the modification shown in FIG. 5.

I claim:

The ornamental design for a detachable handle for a beverage can or the like, as shown and described.
